EX

4194

PATENTED JUN 28 1870

I. Omensetter, assignor to
SAMUEL MACFERRAN
DESIGN FOR
IRON RAILING.

United States Patent Office.

ELHANAN OMENSETTER, OF PHILADELPHIA, PENNSYLVANIA, ASSIGNOR
TO SAMUEL MACFERRAN, OF SAME PLACE.

Design No. 4,194, dated June 28, 1870.

DESIGN FOR IRON RAILING.

The Schedule referred to in these Letters Patent and making part of the same.

I, ELHANAN OMENSETTER, of the city of Philadelphia, and State of Pennsylvania, have invented and produced a new and useful Design for Iron Railings, of which the following is a specification.

The photograph represents a side elevation of a panel of a fence composed of longitudinal rails A A' and open pales B.

The pales B are constructed with multiform open scroll and leal-work, having its seat on the bottom rail A, and terminating above the upper rail A'.

The letter S is traceable in the scroll-work between the rails A A'.

Connected with the lower turn *a* of the scrolls of each pale there is a drop or pendant, *b*.

On the rail A, and in connection with the lower turn *a* of the scrolls, are leafed ornaments *d*.
Similar ornaments are on the rail A'.

The rails A and A' have, at their ends and between the pales B, ornamental bands *e*.

I claim as my invention—

The design for iron railing, as shown.

In testimony that the above is my invention I have hereunto set my hand and affixed my seal this 23d day of April, 1870.

ELHANAN OMENSETTER. [L. S.]
